Primary Examiner — Ralf Seifert*(74) Attorney, Agent, or Firm* — Bacon & Thomas, PLLC(57) **CLAIM**

The ornamental design for a strap retainer, as shown and described.

DESCRIPTION

FIG. 1 is a front perspective view of a strap retainer for use in an orthopedic device, showing our design.

FIG. 2 is a front elevational side view of the strap retainer of FIG. 1.

FIG. 3 is a top plan view of the strap retainer of FIG. 1.

FIG. 4 is a first side elevational view of the strap retainer of FIG. 1.

FIG. 5 is a second side elevational view of the strap retainer of FIG. 1.

FIG. 6 is a rear elevational view of the strap retainer of FIG. 1; and,

FIG. 7 is a bottom plan view of the strap retainer of FIG. 1. The broken lines are included for the purpose of illustrating environmental structure and form no part of the claimed design.
